Patented Sept. 19, 1922.

Fig. 2.

INVENTOR.

Martin A. McDonald.

UNITED STATES PATENT OFFICE.

MARTIN A. McDONALD, OF OAKLAND, CALIFORNIA.

PLAYING HOOP.

Application filed November 6, 1920. Serial No. 422,127.

To all whom it may concern:

Be it known that I, MARTIN A. McDONALD, a citizen of the United States, residing at Oakland, in the county of Alameda and 5 State of California, have invented certain new and useful Improvements in a Playing Hoop, of which the following is a specification.

This invention relates to amusement devices for children and more particularly to hand propelled hoops.

The primary object of the invention is to provide an amusement device in the form of pulling hoops having a handle attachment 15 whereby the child may exert a pressure on the handle to cause the hoops to be propelled.

Another object of the invention is to provide a propelling attachment for a hoop which will cause the hoop to be maintained 20 in an upright position while being propelled.

A still further object of the invention is to provide means whereby a moving figure or manikin may be moved by virtue of the engagement of the figure with the hoop 25 while it is in motion.

Other objects of the invention will appear upon consideration of the following detail description and accompanying drawings, wherein:—

30 Figure 1 is a side view of the hoop constructed in accordance with my invention, showing the attachment applied thereto, the handle being shown in a position to more clearly disclose the construction.

35 Figure 2 is a section taken on the line 2—2 of Fig. 1.

Referring to the drawing by numerals, the hoop 1 is of circular formation and the attachment 2 is adapted to be mounted 40 thereon. The attachment consists of a segmental portion 3 of heavy wire having one end provided with loops or coils 4 through which the hoop is passed and the terminal of the coil 4 is provided with an extension 45 shank 5 which extends at right angles from the loop 4 and has its terminal provided with a handle 6. Attention is respectfully directed to Fig. 1 of the drawings wherein the shank 5 of the handle is shown slightly 50 distorted to more clearly disclose the construction, but it should be understood that

the handle must project at right angles from the attachment member so that the device may be conveniently gripped by the person using the hoop.

55

The opposite end of the segmental portion 3 of the wire is also provided with a guide loop or coil 8 which receives the hoop at the highest portion thereof to maintain it in an upright position while being used so that 60 tilting or falling of the hoop will be prevented while it is in a stationary position, thus facilitating its use while walking or moving at slow speed.

From the coil or loop 8 an upwardly extending standard 9 projects which has its upper end provided with a supporting arm 10 terminating in a loop 11. A jointed figure or manikin 12 is suspended from the loop 11 and the portions of the manikin designating the feet of the figure are engaged with the periphery of the hoop as shown to advantage in Fig. 1. Obviously when the hoop is rotated the figure will be jostled on its support and caused to move thereby giving 70 a novel appearance to the hoop and enhancing its amusing qualities.

Minor changes may be made in the details of construction without departing from the spirit of the invention or the scope of the 80 claim hereunto appended.

What is claimed is:—

A playing hoop comprising a circular hoop, an attachment bracket comprising a segmental length of wire conforming to the 85 shape of the hoop and having each end provided with a coil through which the said hoop passes, the uppermost coil being located at the highest portion of the hoop, the lowermost coil being provided with a right 90 angularly extending shank having a handle at its terminal, the upper coil being provided with a vertical support, having a forwardly projecting arm, and a movable figure suspended from the arm and having its lower 95 end engaged with the periphery of the hoop.

In testimony whereof, I have affixed my signature in the presence of two witnesses.

MARTIN A. McDONALD.

Witnesses:

N. H. TUCKER,
MARY A. McDONALD.
